UNITED STATES PATENT OFFICE.

EDWARD E. CLEMENT, OF WASHINGTON, DISTRICT OF COLUMBIA, ASSIGNEE, BY
MESNE ASSIGNMENTS, TO JAMES R. GARFIELD, TRUSTEE, OF CLEVELAND, OHIO.

TELEPHONE-EXCHANGE SYSTEM.

1,200,811.

Specification of Letters Patent. Patented Oct. 10, 1916.

Application filed August 15, 1911. Serial No. 644,073.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

My invention relates to telephone exchange systems, and especially to those employing so-called automatic switches for interconnecting lines. In such systems it has heretofore been customary to send current impulses from the calling subscriber's station, or from an operator's position, to the switches for the purpose of actuating the latter. In either case, in a system of any considerable size, the individual subscriber's or operator's impulse sender becomes associated at different times with many different switches, and while the rate of transmission of impulses from the sender remains the same, the variation in line resistance and in the time constants of different relays as well as the switches themselves, render the working to a certain extent marginal.

It is the object of the present invention to eliminate the uncertainty resulting from this marginal condition, so that irrespective of conditions, all switches will work well in connection with any sender. I attain this object by providing each switch with means to make and break its own actuating circuit, as a result of its actuation, and I construct the senders so that they will respond to the impulses thus produced in the actuation of any switch, and will act merely as means for limiting the extent of the actuation, instead of causing the same.

The present invention is in the nature of an improvement over the inventions described in certain prior applications, as follows: Serial No. 306,292, filed March 15, 1906; Serial No. 323,096, filed June 23, 1906; Serial No. 327,096, filed July 20, 1906; Serial No. 345,167, filed November 26, 1906; Serial No. 408,039, filed December 26, 1907; and Serial No. 428,865, filed April 23, 1908.

The invention is illustrated in the accompanying drawings in which—

Figure 1 is a diagram showing a simple form of sender at a subscriber's station, and the subscriber's line terminating at a switch through which other lines may be reached.

Fig. 2 is a diagram of a four digit sender with central office connections to a trunk line leading to a first selector switch. Fig. 3 is a diagram showing the first selector switch constituting the selective terminal of the trunk in Fig. 2, also a second selector and a connector switch, the whole constituting part of a central office equipment serving up to ten thousand lines.

Referring to Fig. 1, 1 is the line extending from the subscriber's station 2 to a central office or another station 3, and provided at 3 with a ten point selective switch 4 adapted to have its wiper arms 5 stepped around over the contacts 6 through the agency of a ratchet 7 secured on the shaft of the wiper arm, and actuated by a pawl 8 carried on the end of the armature lever of an electromagnet 9. The windings of magnet 9 are included in a branch circuit 10 containing a pair of normally closed contacts 11 adapted to be opened each time the armature of the magnet is fully attracted. Thus the application of battery to the line 1 will produce intermittent energization of the magnet 9 and correspondingly intermittent actuation of the ratchet 7 to drive forward the wiper arm 5. At the subscriber's station 2 the telephone 12 is normally disconnected as usual at the switch 13, and a branch wire 14 is taken off through the sender 15 to battery and ground. The sender consists essentially of a metal dial 16 having a tooth 17 which normally opens the spring contacts 18-19, a setting hand 20, a retractile spring 21, and ratchet or star wheel 22, and an anchor escapement 23 controlled by the electromagnet 24. It will be understood of course that this diagram is presented as showing the simplest possible embodiment of the principle involved, without any detail. For example the telephone 12 is supposed to be typical of the full subscriber's equipment, as is the telephone 25 at the right hand station; the single conductor wire 1 is typical of the ordinary metallic circuit, and the switch 3 represents any standard switching equipment, with all necessary means for controlling and restoring it at the conclusion of a conversation. In operation the subscriber at 2 in order to select a wanted correspondent as for example at 25, and whose number is 4, pulls down the arm 20 until it registers with the numeral 4. By so doing the tooth 17 is 110

carried away from the spring 18 which closes upon spring 19 and completes the following circuit: B, 24, 14, 18, 19, 14, 1, 10, 11, 10, 9, ground and B. Magnet 9 is energized and attracts its armature, steps the ratchet forward one step, carrying the wiper 5 onto the first contact, and then opens the contact 11. Magnet 24 is simultaneously energized and permits the spring 21 to turn the disk 16 and the ratchet 22 backward one-half step. The breaking of the circuit at 11 deenergizes both magnets 9 and 24, the pawl 8 of the former is retracted, and the ratchet 22 with the arm 20 at the substation 15 are stepped back another half step. The springs 11 being then closed both magnets are again energized, and this operation is repeated four times in all so that the arm 5 rests upon No. 4 contact, when the tooth 20 17 at the substation reaches the spring 18 and finally opens the circuit. The telephone 12 may then be used for conversation.

Referring now to Fig. 2, the substation 25 is shown equipped with a standard common battery telephone set, from which the line wires 26—27 extend to the central office and terminate on contacts of a cut-off relay 28 through which they are normally connected to a line relay 29 and battery on one side and ground on the other. The arrangement shown is the so-called two wire multiple, with extensions 30 and 31 to the jack 32, with which coöperates a plug 33 having its tip and sleeve conductors connected to the cord conductors 34 and 35, terminating at the condensers 36. Tip and sleeve relays 37 and 38 are provided as usual with this type of cord and jack, the relay 38 controlling battery supply to the cord, and being energized in series with the cut-off relay 28 when the plug is in the jack. The relay 37 controls the circuit of the supervisory lamp 39 and the release circuits 40—41 for the automatic switches in Fig. 3, these circuits being connected to the trunk conductors 42—43 extending to the first selector switch 44, which has the usual vertical and rotary relays 44^a and 44^b, private magnet 44^c, test relay 44^d, release magnet 44^e, talking wipers 44^f, test wiper 44^g, side switch arms 44^h, 44ⁱ, 44^j and 44^k, vertical magnet 44^m and rotary magnet 44ⁿ. The second selector switch 45 has relays, magnets and contacts corresponding to those of the first selector with the exception that the vertical and rotary relays of the second selector when simultaneously energized close their own release circuit and also a branch through the test bank and test wiper of a first selector 50 temporarily connected therewith, to the release relay of said first selector. The connector switch 46 has vertical and rotary magnets and relays, and a test or private normal magnet, similar in other functions 55 to those of the selectors. The vertical and

rotary relays control their own release circuit and also the back release the same as in the second selector, but the functions of the magnet 46^c include the test of the line wanted, and the release of the switch if that line is busy. The trunk wires 50—51 of the connector terminate at the condensers 47 and on the switch side of the condensers the conductors 52 and 53 are extended through contacts of the ringing relay 46^p to the side switch arms 46ⁱ and 46^j, by which they are connected during conversation to the talking wipers 46^f, and thereby connected to the contacts of the wanted line.

Further detailed description of the line and cord circuit in Fig. 2 and the general switch circuits in Fig. 3 will not be given, as none of the features so far mentioned form any part of the present invention, except in so far as they contribute to completeness. The circuits illustrated in Fig. 3 are those of the ordinary well known Strowger system, employing selector and connector switches of the type shown in Letters Patent granted to Keith & Erickson March 18, 1906, Nos. 815,176 and 815,321. In order to enable the connector circuit of Fig. 3 to be employed with a two wire multiple line circuit as shown in Fig. 2, the Strowger circuit is modified by the introduction of condensers 47, the tip and sleeve relays 46^a and 46^b, and the ringing relay 46^p with its interrupter 46^s and lockout relay 46^t. These parts are substantially as shown and described in my prior application serial No. 428,865, filed April 23, 1908, and also form no essential part of the present invention.

For the purposes of the present invention, and in order to enable each of the switches 44, 45 and 46 to generate its own actuating impulses, I provide the vertical magnets 44^m and 45^m with interrupter contacts *x* controlled by the magnet armature, these contacts in each case being normally closed and included in the circuit of the vertical relay 44^a or 45^a. In the case of the connector, the vertical and rotary magnets 46^m and 46ⁿ are each provided with interrupter contacts *x*, both pairs of which are normally closed and included in series in the circuit of the vertical relay 46^a. The result of this arrangement is that without other change in any switch, when any one of the actuating magnets is properly connected by means of the side switch, it will make and break the circuit of its associated controlling relay, which in turn will make and break the magnet circuit, thus producing a reciprocal action which insures not only complete operation of the working magnet for each step, but also sends back sharp clear line impulses to affect the relays of the sender.

Turning to Fig. 2, the operator's sending device is generally designated by the nu-

meral 100. It consists of four rotary disks 101, 102, 103 and 104, each of which is fitted with means for turning it through different determinate angles by hand. In 5 the diagram the means indicated are arms with finger holds which serve also as pointers to sweep over numbered arcs. Connected to each disk is a ratchet or star wheel 101^a, 102^a, 103^a or 104^a. These are controlled by 10 anchor escapements carried on the armature levers of electromagnets 105, 106, 107 and 108. Associated with the disks are relays 109, 110, 111, and 112, controlling the actuating magnets and responding to the line 15 impulses in succession. Each disk has a retractile spring, and each scape wheel has a portion of its surface smooth, to permit the spring to move the disk back some distance after the working impulses cease. 20 During this extra movement of each disk it carries a tooth 101^b, 102^b, etc., past contacts to send a rotary impulse, and into engagement with other contacts which shift the control circuit to the next disk. 113 is the 25 starting relay, which connects the vertical and rotary wires 114 and 115 to the trunk wires 42 and 43, in response to the actuation of the starting key 116. In addition to the contacts of this relay I have shown a key 30 117 individual to each trunk, so that the sender 100 may be used with a considerable number of trunks 42—43. This mode of connection however is intended merely for descriptive purposes and not as a limitation. 35 It may be varied in any of the ways described in my prior applications Serial No. 323,096, filed June 23, 1906; Serial No. 327,096, filed July 20, 1906; Serial No. 345, 167, filed November 26, 1906; Serial No. 408,039, filed December 26, 1907; and Serial No. 428,865, filed April 23, 1908. It should also be understood that the plug and cord connection between the trunk wires 42—43 and the line wires 26—27 may be replaced 45 by any desired primary selecting means, such as shown in any of the applications herein named; or the line may be connected direct to the trunk conductors, with condensers 26 interposed if desired. The sender 50 100 may also be located at a subscriber's station as well as at a central office, the necessary changes to effect this or other modifications referred to being well within the scope of any telephone engineer or circuit man. 55 The operation of the apparatus and circuits in Figs. 2 and 3 is as follows: The subscriber 25 calls by closing his line circuit, relay 29 lights its lamp, plug 33 is inserted in jack 32, relays 38—28 are energized in 60 series, relay 37 is energized, and the operator ascertains the number wanted in the usual or any desired way. If key 117 is employed, it is actuated to cut off the trunk from the cord, and connect conductors 65 42—43 to the contacts of the starting relay 113. The number wanted is then set up by turning the disks 101, 102, 103 and 104 until their respective arms or pointers rest over numerals corresponding to the several digits of the number. The turning of these 70 disks completes the circuits of their respective relays 109, 110, etc., and turns the ratchets 101^a, 102^a through angular distances corresponding to the several digits. The starting key 116 being depressed, circuit of 75 relay 113 is closed as follows: B, 118, 119, 116, 220, 113, ground, B. The energization of relay 113 connects 114 to 150 and 115 to 151, and the relay locks itself on wire 149. Circuit is then completed from the battery 80 to the switch 44 in Fig. 3 as follows: B, 118, 109, 141, 123, 122, (101 being off normal) 114, 150, 42, (into Fig. 3) 44^a, x, 44^a, ground, B. Magnet 44^a is energized, closing circuit of 44^m, which is energized and 85 breaks the contacts x apart at the end of its stroke, but steps the switch spindle and wipers up one step before breaking. The separation of contacts x opens the circuit of relay 44^a, which becomes deenergized 90 and in turn opens the circuit of magnet 44^m, which becomes deenergized and closes contacts x thereby closing the former circuit of relay 44^a, which again becomes energized, again energizes magnet 44^m, and so on, the 95 stepping up of the switch 44 and the making and breaking of the circuit at x being repeated so long as the springs 122—123 in Fig. 2 remain closed. These springs are 100 opened when the arm of disk 101 has been returned to zero, which requires as many current impulses as the forward steps through which it was moved in setting. As each current impulse is produced in the 105 actuation of the switch 44 one step, it is obvious that the switch has been set forward or upward a number of steps corresponding to the digit previously determined. 110 The disk 101^a has ratchet or star teeth only part way around its circumference, there being ten teeth on each side and smooth spaces intervening. This is for the purpose of permitting lost motion after the number has been received, so that the spring sets 115 220—121 and 122—123—124 may be operated in succession. The closure of the first named set produces a rotary impulse for the switch 44 through the following path: B, 118, 145, 220, 121, 115, 151, 43, 44^a, 44^b, ground, B. 44^b becomes energized and 120 closes the circuit of 44^c, which becomes energized and steps the side switch arms all around one step, shifting the trunk wire 42 onto a dead contact and closing circuit of 125 rotary magnet 44^a, which rotates the spindle and wipers to find an idle trunk to a second selector, in the ordinary manner. In the meantime the disk 101 being forced past spring 220 by its retractile spring, shifts 130 wire 114 from relay 109 to the path 152, and

thereby connects relay 110 to the trunk 42. When an idle trunk has been found, the side switch of selector 44 takes its last step, as well understood without explanation, and 5 the trunk wire 42 is at once connected to 48, whence a circuit is established from 102 to 45 as follows: B, 118, 110, 142, 128, 127, 152, 124, 122, 114, 150, 42, 48, α , 45^a ground to B. The operation of selector 45 then 10 ensues in precisely the same manner as that of selector 44, and when the disk 102 reaches zero position a rotary impulse is sent over the path: B, 118, 146, 125, 126, 152, 115, 151, 43, 49, 45^b, ground, B. Selector 45 then 15 finds an idle trunk to a connector 46, wire 48 in the meantime remaining open at the side switch, and at the end being connected to 50. A path for the third set of impulses is then closed as follows: B, 118, 111, 143, 20 134, 132, 154, 129, 127, 152, 124, 122, 114, 150, 42, 48, 50, α , ω , (in series) 46^a, ground to B. 46^a actuates the magnet 46^m to step the switch up to the desired row, when the disk 103 operates as the preceding disk 25 mechanisms did, to cut off relay 111, send a rotary impulse and shift the circuit 154 to the next path, 155, leading to the relay 112. In the connector the side switch has shifted in response to the rotary impulse at ω , so 30 that 46^m is cut out and 46^a is cut on to be controlled by 46^a. Further impulses from α follow this path: B, 118, 112, 144, 140, 139, 155, 133, 132, 154, 129, 127, 152, 124, 122, 114, 150, 42, 48, 50, to relay 46^a through 35 ω — ω . Magnet 46^a then steps the switch around to the wanted line terminals and the next rotary impulse causes the line to be tested, and if clear the side switch takes its last step, 46^t and 46^d connecting the trunk 40 wires 52 and 53 to the line through wipers 46^t. Relay 46^r connects the ringing relay to battery, the interrupter 46^s causes its intermittent energization, the wanted subscriber is rung, and when he answers the relay 46^u 45 causes the energization of the lockout relay 46^t, and conversation proceeds. In the meantime, the final step of disk 104 after sending the rotary impulse over wire 153 opens 144 at 140—139, and also opens the 50 locking circuit 148—149 of relay 113, whereby the sender 100 is entirely cut off from the trunk wires 150—151, 42—43. The operator may then throw up the key 117, or if this key is replaced by an automatic secondary selector of the type set forth in my prior applications referred to she 55 will not have to perform any act, but merely wait to receive other calls.

60 While I have described this system as employing Strowger switches and plugs and jacks for connecting calling lines, it is to be understood that I may apply it to switching systems of my own and other improved types, the essential feature being that the 65 impulses should be generated in the actua-

tion of the selective switches and by them transmitted to the so called senders instead of the reverse as heretofore; said senders moreover being completely set up for entire numbers in advance of the first actuation of 70 the switching devices.

Various changes in the apparatus and circuits herein described will occur to those skilled in this art, and I contemplate all such changes of non-essential features or details, 75 as within the scope of the appended claims.

Having thus described my invention what I claim and desire to secure by Letters Patent is:

1. In a switching system, a circuit terminating in a selector switch, a stepping magnet for said switch, contacts controlled by said magnet in its actuation to produce impulses in said circuit, and a sender comprising a circuit closing device adapted to be set 80 so as to close the line circuit and thereafter to be advanced through a variable distance, means adapted to be controlled by the impulses in the circuits to step said sender back into normal or zero position and open the 85 line circuit so as to interrupt the transmission of impulses when the zero position is reached, whereby the extent of automatic movement of the selector switch may be determined in advance, by the extent of movement of the sender, and a second stepping magnet for said switch operating to step said switch independently of said sending device.

2. In a telephone exchange system, a circuit extending to a selector switch, actuating means and an electro-magnet controlling the same for advancing said switch by successive steps, a circuit interrupter controlled in the operation of said electromagnet, and a 100 sender or variable signal controller for the switch comprising a circuit closing device normally open but adapted to be closed in the initial setting of the sender, a movable element and an electromagnet adapted to 105 actuate the same step by step, a connection from said magnet through said circuit closing device to the main circuit governed by said circuit interrupter, whereby said movable element may be caused to step through 110 any desired predetermined number of steps and thereafter to operate said circuit closing device so as to disable said magnet, by opening the line circuit to stop further movement of the selector switch, and a second stepping 115 magnet for said switch operating to step said switch independently of said sending device.

3. In a telephone exchange system, a selector switch and trunk, a stepping magnet 120 for the switch, a relay having its windings connected to the trunk and its contacts controlling a local circuit containing the windings of said stepping magnet, a pair of normally closed contacts included in series in 125

the circuit of said relay windings and adapted to be opened when said stepping magnet is energized, a sending device normally disconnected from the trunk, comprising a movable element and circuit disabling means, with a step by step magnet for actuating said element in response to impulses received from the trunk from said contacts controlled by said stepping magnet, and a starting relay governing the initial closure and final opening of the circuit of said step by step magnet, and the connection of said sending device to the trunk, together with means controlling the circuit of said relay.

4. In a telephone exchange system, a selector switch and trunk, actuating means for producing two selective motions of the switch, means controlled in the actuation of the switch to transmit two sets of impulses over the trunk, a circuit controlling member for the trunk adapted to be operated by the impulses thereover successively and in synchronism with the movements of said switch, adjustable means associated with said circuit controller adapted to be set held in advance to limit the extent of both of the synchronous operations of said switch and of said circuit controller, manually controlled means for starting the synchronous operation of said circuit controller when set, together with automatic means terminating said operations at the end of a predetermined movement.

5. In a telephone exchange system, subscribers' lines, a series of two-motion automatic switches and links for interconnecting them, means for actuating each switch, a plurality of limit devices located at a common point, one for each link of the series, means whereby said limit devices are operated through the primary motion of the switches of the links to disable the actuating means of the switches, means for operating said limit devices to effect said disablement in the order in which the links of the series are built up, means for individually setting said limit devices to predetermine the operation thereof for each link, together with means controlled by the switches to interpose time intervals in the order of operation of the said limit devices dependent upon the completion of the secondary motion of the switch and connection with the next link of the series.

6. In a telephone exchange system, subscribers' lines, a series of automatic switches and links for interconnecting the same, means for actuating each switch, a limit device operable from each link in the actuation of its switch and adapted upon operation to disable the actuating means of the switch, means for setting each of said limit devices to predetermine the extent of actuation of the corresponding switch, means controlled jointly by the switches of the

links and by the limit devices themselves to successively operate them in the order in which the links are built up, a starting relay adapted to connect and disconnect said limit devices from the links together with a locking circuit for said starting relay closed through normally open contacts associated with the last device of the series.

7. In a telephone exchange system, in combination, subscribers' lines, a plurality of step by step switches and switch links for interconnecting the same, actuating magnets for the switches in circuits local thereto, repeating relays for the actuating magnets, means associated with each switch and operative when said switch is in position to connect the actuating magnet relays of a succeeding switch of a series of links, to disconnect its own relays, a limit device operable through the actuation of the switches of the links to disable the actuating magnets of the same to predetermine the actuation thereof, said limit device being operable from the switch through the circuit including the repeating relays only.

8. In a telephone exchange system, subscribers' lines, a series of automatic switches and links for interconnecting the same, actuating means for the switches, a plurality of limit devices located at a common point and connected in a normally closed series circuit associated with the links, means for setting each limit device to predetermine the actuation of the automatic switch of the corresponding link, contacts in the aforesaid series circuit associated with each limit device operated during the setting of said limit device to break said circuit into a plurality of parts, additional control means in said series circuit whereby the limit devices when operated disable the actuating means of the switches and means associated with the branches of the said series circuit and responsive to the actuation of the switches of the links to progressively restore the continuity of said series circuit, whereby the limit devices are successively cut in to control the switches of the successive links.

9. A telephone exchange system, comprising subscribers' lines, a series of automatic switch links and switches for automatically connecting them, actuating means for the switches, a limit device operated through the actuation of the switches, and governing said actuating means, means for setting said limit device with respect to the switches to determine the operation thereof to disable actuating means, and means to produce shifting impulses for said switches actuated by the switches themselves.

10. A telephone exchange system, comprising subscribers' lines, a series of automatic switch links and switches for interconnecting them, actuating means for the switches, a limit device operable by said

- switches to determine the actuation thereof, means for setting said limit device with respect to said switches to enable said actuating means for a predetermined number of steps of said switch, means operable by said limit device in its return to normal movement to send a shifting impulse to the actuating switch.
11. A telephone exchange system, comprising subscribers' lines, a series of automatic switch links and switches for interconnecting them, actuating means for the switches, a step by step limit device operated through the actuation of the switches and governing said actuating means of the switches, means for setting said limit device to predetermine the disablement of the actuating means of the switches as respects the number of steps taken by the device, and means operable upon the last step of the limit device to send a shifting impulse over the link circuits.
12. A telephone exchange system, comprising subscribers' lines, a series of automatic switch links and switches for interconnecting them, actuating means for the switches, a normally idle limit device retaining the actuating means of the switches disabled, means for setting said limit device to enable the actuating means of the switches for a predetermined number of steps of the switches, together with means whereby said limit device is returned to normal disabling position by said switch synchronously with the stepping of the same, and means operable by the limit device after the last step of the switch to send a shifting impulse to the links.
13. In a telephone exchange system, subscribers' lines, a plurality of automatic two-motion switches and links for interconnecting the same; primary actuating means for the switches, secondary actuating means for the switches, a limit device operable through the actuation of the switches to disable the primary actuating means of the same, means for setting said limit device to predetermine the limit of said primary motion of the switches, means automatically controlled by said limit device in its operation by the switches to send a shifting impulse over said links to initiate secondary motion of the switches.
14. In a telephone exchange system, subscribers' lines, a series of two-motion automatic switches and links for interconnecting them, a plurality of limit devices, one for each link located at a common point and adapted to be connected in succession to the links of the series as they are built up, primary actuating magnets for the switches, secondary actuating magnets for the switches, operating means for the limit devices controlled through the actuation of the switches by the primary actuating means, and circuit closing means associated with each switch and successively extending the connection of the limit devices to the primary actuating means exclusively of the secondary actuating means.

In testimony whereof I affix my signature in presence of two witnesses.
